[57] CLAIM

The ornamental design for a bottle, as shown and described.

DESCRIPTION

FIG. 1 is a perspective view of a bottle showing my new design;

FIG. 2 is a front elevational view of FIG. 1, the rear elevational view being the same;

FIG. 3 is a right side elevational view of FIG. 1, the left side elevational view being the same;

FIG. 4 is a top plan view of the design according to FIG. 1; and,

FIG. 5 is a bottom plan view of the design according to FIG. 1.

The broken lines showing a cap are for illustrative purposes only and do not form part of the claimed design.
